UNITED STATES PATENT OFFICE

159,458

INTERCOMMUNICATION UNIT OR THE LIKE

Benjamin J. Zapolski, New York, N. Y., assignor
to Electronational Engineering Co., Long Island
City, N. Y., a partnership of New York

Application October 20, 1949, Serial No. 5,591

Term of patent 14 years

(Cl. D26—14)

To all whom it may concern:

Be it known that I, Benjamin J. Zapolski, a citizen of the United States of America, residing at New York, county of New York, State of New York, have invented a new, original, and ornamental Design for an Intercommunication Unit or the like, of which the following is a specification, reference being had to the accompanying drawing, forming a part hereof.

In the drawing:

Fig. 1 is a perspective view of an intercommunication unit or the like illustrating my new design.

Fig. 2 is a front elevational view thereof.

Fig. 3 is a side elevational view thereof.

I claim:

The ornamental design for an intercommunication unit or the like, substantially as shown.

BENJ. J. ZAPOLSKI.
